United States Patent Office

Des. 193,392
Patented Aug. 14, 1962

193,392

GLASS BLOCK

Howard F. Kingsbury, Port Allegany, Pa., assignor to
Pittsburgh Corning Corporation, Pittsburgh, Pa., a corporation of Pennsylvania

Filed Oct. 9, 1959, Ser. No. 57,875

Term of patent 14 years

(Cl. D18—2)

FIG. 1

FIG. 2

FIG. 1 is a front perspective view of a hollow glass block, showing my new design; and FIG. 2 is a cross-sectional view taken on line II-II of FIG. 1.

The other side, bottom and rear are substantially like the respective side, top and front shown.

I claim:

The ornamental design for a glass block, as shown and described.
